UNITED STATES PATENT OFFICE.

LEO EHRLICH, OF ST. LOUIS, MISSOURI.

CASH-REGISTER.

SPECIFICATION forming part of Letters Patent No. 681,633, dated August 27, 1901.

Application filed September 29, 1898. Serial No. 692,179. (No model.)

To all whom it may concern:

Be it known that I, LEO EHRLICH, a citizen of the United States, residing at St. Louis, in the State of Missouri, have invented a certain 5 new and useful Improvement in Cash-Registers, of which the following is a specification.

My invention relates to the improvement of cash-registers, and has particular relation to improved means for resetting the amount- 10 registering wheels of a cash-register back to zero or a desirable starting-point.

The objects of my invention are to provide a simple, reliable, and effective device of this class which will be adapted for use on cash- 15 registers which employ a set of registering-wheels journaled or mounted upon a key-shaft, to so construct the same as to reset or return the wheels to a common starting-point in a simple and reliable manner, and to pro- 20 duce other improvements in details of construction and arrangement of parts, which will be more fully pointed out hereinafter. These objects I accomplish in the manner illustrated in the accompanying drawings, in 25 which—

Figure 1 is a face view of that portion of a cash-register mechanism which contains the registering-wheels. Fig. 2 is a similar view showing the registering-wheels at the conclu- 30 sion of the operation of my improved resetting device. Fig. 3 is a sectional view on line xx of Fig. 1. Fig. 4 is a similar view on line zz of Fig. 2. Fig. 5 is a detail view of a spring-actuated pawl which I employ in the manner 35 hereinafter described, and Fig. 6 is a sectional view through the casing and the operating parts.

Similar numerals refer to similar parts throughout the several views.

40 In the class of cash-registers to which my improvement applies one or more sets of registering-wheels 1 and 2 are rotatably mounted upon a shaft 3, means being provided which are not herein shown and which do not form 45 a part of my present invention for rotating said wheels the desired distances. The registering-wheels 1 and 2 are provided with numbered peripheries, each wheel containing the desired number or set of numbers or 50 figures, each set running from "0" to "9," and each of said wheels being provided on one side with projecting teeth 4, one of said

teeth being arranged opposite each number or figure thereon. As indicated at 5, I provide the periphery of each of the registering-wheels at equidistant points thereon with projecting lips, the latter being, as shown, arranged between the sets or between the first figure of one set and the last figure of the adjoining set of numerals which are stamped or otherwise made to appear upon the wheel-periphery.

6 represents spring brake-strips which, as indicated in the drawings, are mounted to depend from a transverse frame-rod 7, which 65 extends between the upper portions of frame-standards 8. One of these spring brake-strips is, as shown, provided for each of the wheels 1, and the lower ends thereof are adapted to engage with the teeth of said wheels and 70 prevent the latter from reversed rotation.

In the class of cash-registers to which my invention applies it has been common to rotate the registering-wheels by the engagement of the finger with the teeth 4 or lip pro- 75 jections 5 until the naught on each wheel appears immediately below and in front of the brake-spring 6, which engages therewith. The means which I employ for this purpose 80 may be described as follows.

Upon the shaft 3 I fulcrum adjacent to each of the registering-wheels a bell-crank lever 9, the latter having its forward and longer arm 10 extending, as indicated more clearly in Figs. 3 and 4, slightly beyond the 85 peripheries of said registering-wheels. On the outer end of each of these bell-crank arms 10 I fulcrum an elongated pawl 11, the lower edge portion of which is adapted to engage with the projecting lips 5 of the adjoining registering-wheel. This pawl is normally pressed inwardly or rearwardly, and thus retained in the path of said lips through the medium of a spring-strip 12, secured to the arm 10 and having its outer hook-shaped end 90 portion bearing against the forward face of the pawl.

Extending transversely between the frame-standards 8 of the machine and opposite the lower portions of the registering-wheels is a 100 rod or shaft 13, upon which is mounted to turn the lower sleeve-shaped portion 14 of a plate or lever 15. With the plate-sleeve 14 I form a short arm 16, and at intervals on

said sleeve are formed projecting arms 17, which extend at right angles with the arm 16. The arms 17 are through the medium of bars or rods 18 jointedly connected with 5 the respective arms 10^a of the bell-cranks 9. Pivoted to the outer end of the arm 16 is the lower end of an upwardly-extending and inwardly-inclined rod 19, the upper portion of which passes loosely through an opening in 10 a fixed projection 20 of the transverse frame-rod 7. The rod 19 is provided with a shoulder portion 22, and between the latter and the under side of the projection 20 said rod is surrounded by a coiled spring 23. This rod 15 lies on one side of the line drawn from the opening in the projection 20 to the shaft 13 when the lever 15 is in one position and upon the other side when the lever is in its other position. As will be understood, the tension 20 of the spring 23 is thus exerted to hold the lever in either of its two extreme positions.

Extending between the frame-standards 8 is a transverse frame-rod 24, against the outer side of which the upper portion of the 25 plate or lever 15 is adapted to bear. When said plate or lever 15 is in the elevated position shown in Figs. 1 and 3 of the drawings, it is obvious that the same will be retained in contact with the rod 24 through the 30 pressure of the spring-actuated rod 19 on the arm 16.

In registers of this class it is common to read the amounts registered by the wheels at points immediately in front of the lower end 35 portions of the brake strips or pawls 6, and in order to so reset the registering-wheels as to cause each of said wheels to display a cipher at the above-described reading-point the plate or lever 15 is pulled outward and downward 40 to the horizontal position indicated in Figs. 4 and 2 of the drawings, resulting in a swinging movement being thereby imparted to the bell-cranks 9 and the consequent contact of the pawls 11 and the next lower lips 5 of the 45 wheels. The degree of rotary movement thus imparted to the registering-wheels is thus dependent upon the degree of movement of the bell-crank arms 10, which is so limited as to insure the stopping of the wheels at such 50 points as to display the ciphers or naughts thereon immediately in front of the brake-strips 6. It will thus be seen that where the registering-wheels are provided with numbers arranged in sets running from "0" to "9," 55 inclusive, and the lips 5 are caused to project, as shown, between said sets the one downward movement of the plate or lever 15 will result in all the wheels being reset to zero or naught at the end of any desired time or prior 60 to the beginning of the new registration. In case, however, the numbers on the peripheries of the registering-wheels, as shown on the registering-wheel 2 at the extreme left in the drawings, should number from "0" to "100" 65 or to other multiples of ten the operation of throwing down the lever 15 may be repeated

a sufficient number of times to bring the naught thereon to the desired point.

While I have generally referred to the part 70 15 as a "lever," it may, as shown in the drawings, consists of a broad plate extending over the front portions of all the registers. When so constructed, it forms an inner door, covering the registers, and serves as a guard to the same. When it is opened, as shown in Fig. 75 4, the entire series of registers, if it is a department machine, are automatically and simultaneously reset to zero. By reference to Fig. 6 it will be seen that this inner door is opposite the main door 25 of the casing 26 of 80 the machine. Above the rod 24 there is secured a shield-plate 27, which prevents access to the registers above this door. It will thus be seen that the register can only be reached by opening the plate 15 and that with 85 this construction it becomes impossible for any one to open the machine to change the registers without moving all the register-wheels and so altering the previous registration that the proprietor will know that the machine has 90 been tampered with. It thus becomes the proprietor's detector, for while the register-wheels cannot be reached without opening the door any movement of the same which is sufficient to permit a manipulation of a register 95 will move all the wheels of all the registers, and thereby show an attempt to defraud.

Although I have shown my improvement as used in connection with two sets of registering-wheels, such as are employed in what 100 are known as "department" cash-registers, it is obvious that my device is adapted for use in connection with any desired number of registering-wheels, whether the same be arranged singly or in sets. 105

Having now fully described my invention, what I claim, and desire to secure by Letters Patent, is—

1. In a machine of the character described, a register, a movable guard for said register, 110 and means for setting the register to zero when the guard is moved.
2. In a machine of the character described, a series of registers, a movable guard for the same, and means connected with said guard 115 for simultaneously setting all the registers to zero.
3. In a machine of the character described, a series of registers, and means for causing 120 all the registers to detect any attempt made to fraudulently manipulate any of the same.
4. In a cash-register, the combination with the framework, registering-wheels journaled therein having numbers on their peripheries, and lip projections arranged at intervals on 125 said wheels, of swinging arms, pawls carried on said swinging arms and adapted to engage with said lip projections and means for simultaneously moving said swinging arms predetermined and corresponding distances, 130 substantially as and for the purpose specified.

5. In a cash-register, the combination with the framework, registering-wheels journaled therein, said registering-wheels having peripheral numbers arranged in sets comprising figures from "1" to "10," and lip projections between said sets, of a fulcrumed bell-crank lever for each of said wheels, a spring-actuated pawl carried on one arm of each of said levers and supported in the path of said 10 lip projections, a fulcrumed lever and a jointed connection between said lever and bell-crank, substantially as and for the purpose specified.

6. In a cash-register, the combination with 15 the framework, a shaft supported therein, and registering-wheels journaled on said shaft, said registering-wheels having numbered peripheries and lips projecting at intervals therefrom, of bell-crank levers journaled on 20 said shaft, pawls carried on said bell-cranks and supported in the paths of said wheel-lips, a spring-actuated fulcrumed lever 15 and a

jointed connection between the latter and the inner arm of said bell-crank, substantially as and for the purpose specified. 25

7. In a cash-register, the combination with the framework, a shaft supported therein, registering-wheels rotatably mounted on said shaft, said registering-wheels having numbered peripheries and lip projections at intervals thereon, of bell-cranks 9 fulcrumed on said shaft, one arm of each of said bell-cranks carrying a pawl on its outer portion, the latter being supported in the path of the projecting lips of the adjacent registering-wheel, a fulcrumed lever 15, arms 17 projecting at intervals from the latter, said arms 17 having a jointed connection respectively with the inner arms of the bell-cranks 9, substantially as and for the purpose specified. 30 35

LEO EHRLICH.
